DESIGN FOR AN INTERMEDIATE SECTION OF A FLUORESCENT LAMP FIXTURE SHIELD

Benjamin Schaefer, Jamaica, N. Y.

Application July 25, 1945, Serial No. 120,946

Term of patent 14 years

(Cl. D48—16)

To all whom it may concern:

Be it known that I, Benjamin Schaefer, a citizen of the United States, residing in Jamaica, Long Island, county of Queens, and State of New York, have invented a new, original, and ornamental Design for an Intermediate Section of a Fluorescent Lamp Fixture Shield, of which the following is a specification, reference being had to the accompanying drawing, forming part thereof.

Fig. 1 is a bottom plan view of an intermedi-

ate section of a fluorescent lamp fixture shield showing my new design;

Fig. 2 is an end view thereof;

Fig. 3 is an enlarged section taken on line 3—3 of Fig. 1.

I claim:

The ornamental design for an intermediate section of a fluorescent lamp fixture shield, as shown.

BENJAMIN SCHAEFER.
